UNITED STATES PATENT OFFICE.

AUGUST L. STARKE, OF BROOKHAVEN, NEW YORK, ASSIGNOR TO INSULATION MANUFACTURING COMPANY, INC., A CORPORATION OF NEW YORK.

TERMINAL CASE.

Application filed August 15, 1925. Serial No. 50,365.

This invention relates to an improved form of terminal case or block having therein a series of conductor terminals, each being insulated from the other and so arranged that the various leads which are connected to the terminals will also be insulated from each other and may be properly designated to indicate the leads.

One of the objects of the invention is to provide a case or block of the above mentioned type which is so constructed that the terminals for the leads are not only insulated from each other but are protected from the weather conditions.

Another object of the invention is to so construct the device that the indicating labels, writing strips or markers are easy of access and readily seen.

Other objects of the invention will appear from the hereinafter description and claims.

In the drawing which forms a part of this specification:

Fig. 1 is a plan view of the terminal casting or block embodying my invention, parts thereof being broken away.

Fig. 2 is a side view thereof, a portion being broken away.

Fig. 3 is a section on line 3—3 of Fig. 2, the leads being shown.

Fig. 4 is a perspective view showing a terminal bar.

Inventions of this class are made up to receive either four, eight or twelve pairs of leads but in the present application the device illustrated and described is adapted for a maximum of eight pairs of leads.

The body of the device may be made up of insulating parts such as plates or slabs secured together in ways well known in the art, but the preferred form is an integral casing or block which is made of any suitable moldable insulating material and may thus be pressed up to the desired form in dies by methods well known in the art.

As clearly indicated in the drawings the casing or block is made of a base 10 which is provided with a series of inclined or sloping transverse partitions 11, the upper corners of which are rounded, as shown, in order to avoid sharp projections. In this instance nine of such partitions are provided for a terminal casing constructed to receive eight pairs of leads.

Midway between each pair of transverse partitions and integral therewith and with

the base 10 is a series of partition plates 12 forming ridges arranged longitudinally of the device. These ridges 12 act to divide the space between the transverse plates or ribs into chambers or cells which are thus insulated from each other. Secured to the bottom of each pair of chambers is a metal (preferably brass or copper) bus-bar 13 preferably rectangular in form as clearly illustrated in Fig. 4. Each end of the bus-bar is provided with screw-threaded holes 14 and 15 to receive the screw terminals 16 and 17 by means of which the leads 20 and 21 are properly secured. At the center of the bus-bar a roughened area 22 is provided for the purpose of affording anchoring engagement with the bottom of the longitudinal ridges 12 so as to prevent the bus-bar from being radially dislodged. Other anchoring means may be used for this purpose such as pins or cavities or any uneven surface, all well known in the art.

The longitudinal ridges are preferably flat on top as at 23 and lead from the upper surface of one horizontal partition to a point near the middle of the partition next below as clearly shown in the drawing.

A marking strip 30, consisting preferably of bristol board or strong white paper is secured to the upper face of each transverse sloping partition, which strip is held in place either by being molded thereon during the process of manufacture or pasted or otherwise suitably secured in proper position so that they may be readily utilized to mark thereupon the leads as connected. By utilizing sufficient pressure it has been found practicable to mold a strip of bristol board or heavy paper into the surface of the moldable insulating material such as used in forming the terminal casing or block so that the two surfaces, those of the partition and the card, will be in the same plane.

The transverse partitions 11 are inclined as shown for the purpose of forming sloping surfaces or eaves for carrying away rain and thus protect the terminals from the elements of the weather. The upper surface of the inclined transverse strips also present as above stated a favorable position for the marking strips so that they will not only be readily seen but easily reached.

Each end of the casing is provided with a heavy transverse strip of insulating material through which rivets or screw holes

are formed as at 35 and 36 to receive holding screws 37 and 38 to secure the case to a supporting wall W as more clearly shown in Fig. 2.

5 After the terminal case or block is in position the various leads may be readily connected and adjusted and also identified by the workman making the connection because he is enabled to plainly mark the leads on 10 the respective marking strips.

As is well known, the ends of the leads may be fastened very readily by means of binding screws to the conductor plates or bars and as they are situated in the respective 15 chambers or cells having walls of insulating material they are safe from injury and from short circuiting.

As changes of construction could be made within the scope of my invention, it is intended that all matter contained in the above 20 description or shown in the accompanying drawing, be interpreted as illustrative and not in a limiting sense.

Having now described my invention, what 25 I claim as new and desire to secure by Letters Patent is:

1. A terminal case consisting of a body of insulating material provided with a series of inclined transverse parallel partitions 30 projecting from a face thereof, each partition extending entirely across the case and connected to each other intermediate of their

ends with longitudinally disposed brace- 35 plates, each of said plates extending respectively from the upper surface of one partition to a point near the middle of the partition next below to form pairs of chambers or cells insulated from each other, and a conductor plate or bus bar provided with terminal screws at each end thereof secured to the bottom of each space formed respectively between the trans- 40 verse partitions, each terminal being situated in a chamber or cell of a pair, the transverse partitions being each provided 45 with an uninterrupted exposed upper surface throughout the width of the case.

2. A terminal case consisting of a body of molded insulation having fastening means at each end, a plurality of transverse inclined parallel partitions extending entirely across the body of the case forming recesses therebetween, a longitudinally disposed central row of brace plates dividing each of 50 said recesses into a pair of cells, one cell on each side of a brace plate, a conductor plate provided with a terminal screw in each cell, said plate being secured to the bottom of each recess, and a marking strip secured to the upper face of each lower-most partition, 55 said strip extending uninterruptedly across the body from one cell to the other cell of each pair.

AUGUST L. STARKE.
